UNITED STATES PATENT OFFICE

MICHAEL F. GATELY, OF WESTPOINT, NEBRASKA

BOXING GLOVE

Application filed September 16, 1927. Serial No. 220,018.

The present invention relates to boxing gloves of the pneumatic cushion type. One of the difficulties with gloves of this character is that if the pneumatic cushion is ruptured by a blow, the force of the blow is apt to be delivered direct by the fist of the boxer and do serious injury.

The primary object is to provide means whereby if a cushion is thus ruptured a second cushion is interposed between the fist and the portion that receives the blow.

The preferred embodiment of the invention is illustrated in the accompanying drawings, wherein:—

15 Figure 1 is a perspective view of the glove, Figure 2 is a longitudinal sectional view therethrough,

Figure 3 is a cross sectional view,

Figure 4 is a detail view of the inner side 20 of the rear portion of the glove,

Figure 5 is a detail perspective view of the cushion structure.

In the embodiment disclosed, a hand-receiving pocket member 6 is provided, which 25 may be of any suitable character, having a thumb cot 7 and a cross pad or bar 8. On the outer side of this member 6 is formed a cushion-receiving pocket 9, comprising an outer flexible wall 10, the shape of which is 30 generally that of the well-known boxing glove. This wall 10 is secured to the hand-receiving pocket member 6 by any suitable means, as a seam 11. The rear end of the cushion-receiving pocket member 9 is open, 35 but is adapted to be closed by a flap 12 and suitable lacing 13.

In the cushion-receiving pocket member 9 are located two independent cushion members. The base member is in the form of a 40 doubled pneumatic tube, the legs 14 of which lie alongside each other and are preferably held in place by a transverse stay strap 15 having a tie portion 16 that is located between the legs 14. The rear ends of the tube 45 are located in cap sleeves 17, and one end of said tube is provided with a filling nipple 18. The legs of the tube form between them a longitudinal groove or recessed seat, in which a second and independent pneumatic 50 tube 19 rests, this tube thus overlying the

legs 14, as will be clear by reference to Figure 3. The rear end of the said tube 19 is preferably located in a cap 20 and is provided with a filling nipple 21. These nipples, as will be clear by reference to Figure 2 are accessible 55 through the open rear end of the cushion-receiving pocket member 9.

While the tubes are shown as circular in cross section in Figure 3, it will be obvious that the cross sectional configuration can be 60 altered, and in any event when the glove is doubled by closing the hand into a fist, these cushions will flatten out and produce a smooth contour to the wall 10. Should either one of the tubes be ruptured from a blow, the 65 other will still constitute a cushion, and therefore the danger of the fist striking a blow with only the thin walls interposed between the contacting surfaces is reduced to a minimum. It is not likely that both tubes 70 will break at the same time.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages 75 of the invention.

What I claim, is:

1. A boxing glove comprising means for mounting the same on the hand, a plurality of superposed pneumatic cushions on said 80 mounting means having independent chambers, and means for admitting air into the respective chambers and holding one chamber inflated when the other chamber is deflated.

2. A boxing glove comprising means for mounting the same on the hand, a plurality of superposed pneumatic cushions on said mounting means having independent chambers, and separate inflating nipples for the different chambers.

3. A boxing glove comprising a hand receiving pocket member and a cushion receiving pocket member on its outer side and having an open rear end, a pneumatic cushion tube in the cushion receiving pocket having 100

a filling nipple accessible at the rear end thereof, a second cushion tube in the cushion receiving pocket over the first tube and having a filling nipple accessible at the rear end of the cushion receiving pocket, and means for closing said rear end.

4. A boxing glove comprising a casing having a hand-receiving pocket, a pneumatic cushion in the casing comprising tubular legs located side by side and forming a groove between their outer portions, and a second pneumatic cushion tube in the casing seated in said groove and projecting above the legs thereby constituting the member that receives the initial impact of the blows delivered.

5. A boxing glove comprising a casing having a hand-receiving pocket, a pneumatic cushion in the casing comprising a doubled tube having legs located side by side longitudinally of the casing and forming a groove between their outer portions, a second pneumatic tube in the casing lying longitudinally in the groove and extending beyond the outer side of the legs to receive the initial impact of the blows delivered, and separate nipples whereby the tubes can be separately filled.

In testimony whereof, I affix my signature.

MICHAEL F. GATELY.
